Patented Nov. 6, 1917.

FIG. 1.

FIG. 3.

Wallace F. Root

Inventor

By *Geo. H. Kimmel*
Attorney

UNITED STATES PATENT OFFICE.

WALLACE F. ROOT, OF CUYAHOGA FALLS, OHIO.

RAILWAY-TIE.

1,245,974.

Specification of Letters Patent.

Patented Nov. 6, 1917.

Application filed March 17, 1917. Serial No. 155,517.

To all whom it may concern:

Be it known that I, WALLACE F. Root, a citizen of the United States, and resident of Cuyahoga Falls, in the county of Summit 5 and State of Ohio, have invented certain new and useful Improvements in Railway-Ties, of which the following is a specification.

This invention relates to new and useful 10 improvements in ties, and more particularly a railway tie that is adapted to be disposed transversely beneath a pair of longitudinally extending rails, the said tie being formed of steel, and if desired the steel being embedded 15 in concrete, and means whereby the rails are securely fixed to the upper edge of said tie. This form of tie forms a very strong and efficient rail holder, and also may be quickly 20 detached from the rail, when it is desired to remove the same.

Another object of the invention is to provide a device of this character which is easily and simply constructed, inexpensive to manufacture, and one which will be very efficient in operation.

With these and numerous other objects in view my invention consists of the novel features of construction combination and arrangement of parts which will be herein referred to and more particularly pointed out 30 in the specification and claims.

In the accompanying drawings:

Figure 1 is a side elevation of a portion of the tie showing the rail applied thereto;

Fig. 2 is an end elevation of the tie;

Fig. 3 is a top plan view of a portion of the tie showing one of the openings therein; and

Fig. 4 is a detailed perspective of one of 40 the locking blocks employed to hold the rail in position.

In describing my invention I shall refer to the drawings in which similar reference characters designate corresponding parts 45 throughout the several views. It will be understood that my new and improved railway tie may be used as an all metal tie or the metal may be embedded in a concrete body if desired. In Fig. 1 of the drawings I 50 have shown the tie partially embedded in concrete 1, the same being partly broken away to illustrate the means of attaching the upper edge of the tie 2 to a rail.

My new and improved tie proper, comprises 55 a channeled U-beam 2, which is formed of metal, and when the tie is used with a

concrete body, said beam forms a core therefor that extends longitudinally of said body. The beam 2 is positioned upright, having one side 3 thereof which is designated the 60 lower side resting on the ground when the tie is used as an all metal tie, while the upper side 4 is disposed transversely beneath a pair of longitudinally extending rails, and is connected therewith in a manner to be 65 hereinafter more fully described. The upper side 4 of the beam 2 is provided with a plurality of openings 5 therein, that are disposed adjacent the edges of the base portions 6' of the rails that are disposed transversely 70 or across the said tie. These openings 5 in the upper side of the beam are substantially alike, and for the sake of brevity I will only specifically describe one of the same. This also applies to the attaching 75 means that are associated therewith, and which connect with the edges of the web portions of the rail.

The opening 5 is formed of cross slots 6 and 7, the slot 7 extending longitudinally 80 along the upper side of the tie, while the slot 6 extends transversely across the same. The slot 6 is wider than the slot 7, and the said slot 7 crosses the same adjacent its outer end as clearly shown in Fig. 3 of the 85 drawings. One side of the slot 6 extends obliquely.

Adapted to be positioned through the opening 5 in the upper side of the beam is a block 8 which is formed with notches 9 and 10 in its opposite edges and which has a portion of the upper surface thereof inclined as shown at 11. When the rails are positioned on the upper side of the beam, the edges thereof will be disposed adjacent said openings, and the block 8 is inserted through said opening, the said block being positioned through the opening in the slot 7, and then turned until it is positioned obliquely within the slot 6 in said opening.

In position the notch 9 will engage the edges of the web portion of the rail with the flange of the tie while the notch 10 will engage the opposite side of the slot 6.

To securely lock the block 8 into engaged 105 position, there is provided a wedge locking key 12, that is adapted to be driven between one side of the block, and the adjacent edge of the opening 5, in this instance comprising the adjacent edge of the slot 6. In Fig. 2 110 of the drawing I have clearly shown the application of the wedge to the block, and it

will be seen that the same will securely hold or lock the block within the opening, to fasten the rails to the top of the U-beam.

In operation it is obvious that when the 5 longitudinally extending rails are positioned transversely across the upper side 4 of the tie, and the block and wedge keys are associated therewith, the base portions of the rail will be securely locked to said tie. If 10 desired the beam which forms the main support of the tie will operate without the use of the same. By the use of blocks and wedges of this character, the rails may be quickly disengaged from the tie when it is 15 desired to replace the same.

From the foregoing description of the construction and operation of my new and improved railway tie, the manner of applying the same to use and operation thereof will be 20 readily understood, and it will be seen that I have provided a simple and efficient means for carrying out the objects of this invention.

Having fully described my invention, 25 what I claim as new, and desire to secure by Letters Patent, is:

1. A device of the class described comprising an upright channeled beam adapted to be disposed transversely beneath a pair 30 of longitudinally extending rails, blocks in-

sertible through the upper side of said beam and adapted to engage the edges of said rails, means to lock said blocks in position, and a plastic composition surrounding said beam.

2. In a device of the class described comprising 35 an upright U-beam adapted to be disposed transversely beneath a pair of longitudinally extending rails, the upper side of said beam having openings formed of crossed slots therein adjacent the edges 40 of the rail, blocks having notched edges adapted to be positioned in said openings longitudinally with respect to the rails and to be turned at right angles whereby the notches engage the edges of said rail and the 45 opposite edges of the openings, and wedges to lock said blocks in position.

3. The combination with a concrete tie, 50 of a longitudinally extending metallic core embedded therein comprising an upright U-beam having a pair of rails resting on its upper side, blocks positioned through said upper side of said beam and engaging the edges of the rail, and means for locking said blocks in position to securely fasten the rails 55 to the said upper side of the beam.

In testimony whereof, I affix my signature hereto.

WALLACE F. ROOT.
